UNITED STATES PATENT OFFICE.

MARTIN LANDENBERGER, OF PHILADELPHIA, PENNSYLVANIA.

DESIGN FOR A CAPE.

Specification forming part of Design No. 6,702, dated June 10, 1873; application filed May 8, 1873.

To all whom it may concern:

Be it known that I, MARTIN LANDENBERGER, of Philadelphia, Pennsylvania, have invented a Design for a Garment, of which the following is a specification:

In the accompanying drawing, Figure 1 is a perspective view, and Fig. 2 a skeleton outline, of a circular garment made in accordance with my design.

The garment is of the general semicircular form illustrated in Fig. 2, has a curved recess, *a*, for the neck-band, a hood, *A*, at the back, and is split or slashed at the bottom, as shown at *b*; but this is immaterial and may be dispensed with.

The hood *A* is of the peculiar general shape best observed in Fig. 2, it being drawn in at *c* and provided with pendent ends *d*. The

hood is further ornamented by a row of buttons, by a gimp-like fringe at the edges of the same, and by a deep fringe at its lower extremity, similar to that with which the semicircular outline of the garment is edged.

I claim—

1. The design for the hood *A*, having the outline shown and described.
2. The design for the whole garment, substantially as described, and as represented in and by the accompanying drawing.

In testimony whereof I have signed my name to this specification in the presence of two subscribing witnesses.

MARTIN LANDENBERGER.

Witnesses:

WM. A. STEEL,
HUBERT HOWSON.
